UNITED STATES PATENT OFFICE.

JOHN GUY WYNN, OF MADISON, WISCONSIN.

TIME-RECORDER.

No. 842,990.

Specification of Letters Patent.

Patented Feb. 5, 1907.

Application filed October 28, 1904. Serial No. 230,309.

To all whom it may concern:

Be it known that I, JOHN GUY WYNN, a citizen of the United States, and a resident of Madison, in the county of Dane and State 5 of Wisconsin, have invented a new and Improved Time-Recorder, of which the following is a full, clear, and exact description.

My invention relates to time-recorders and admits of general use, but is of peculiar value 10 in factories, stores, and similar institutions in which it is desirable to make records of the time of various employees.

My invention relates more especially to mechanism for cutting time-cards so as to 15 note, in contrast with each other, the respective times for beginning and finishing different pieces of work.

My invention further relates to various parts and combinations thereof admitting of 20 general use in relation to time-records.

Reference is to be had to the accompanying drawings, forming a part of this specification, in which similar characters of reference indicate corresponding parts in all the figures.

Figure 1 is a perspective view of my device ready for use. Fig. 2 is an enlarged horizontal section through the same, showing the mechanism for holding and cutting the card, 30 and is taken upon the line 2 2 of Fig. 4 looking in the direction of the arrow. Fig. 3 is a fragmentary plan view of the lower shear and the clipping-knife used for cutting the cards. Fig. 4 is a vertical section through the device, 35 showing the time sprocket-chain and the upper and lower shears, together with parts accompanying the same. Fig. 5 is a plan view of one of the cards, showing how the same is cut at the beginning of the work. Fig. 6 is a 40 somewhat similar view, but showing the condition of the card as cut after the work is finished. Fig. 7 is a vertical section upon the line 7 7 of Fig. 4 looking in the direction of the arrow and showing the upper and lower 45 shears, the time-sprockets, and various other mechanical parts; and Fig. 8 is a fragmentary section through the sprocket-chain, showing one of the time-pins.

The casing of the apparatus is shown at 9 50 and is provided with an extension 10. A slot 11 extends downwardly from the top of the casing and is used for the insertion of the card to be cut. Mounted within the casing is a comparatively thick metallic plate 12, through which the slot 11 continues, as

indicated in Fig. 2. An eight-day clock 13 is mounted upon the front part of the casing and is provided with a spindle 14, which rotates once in every twelve hours. This spindle carries a sprocket-wheel 15, rigidly connected therewith. Mounted below this sprocket-wheel is another sprocket-wheel 16. These sprocket-wheels carry a sprocket-chain 17, preferably twenty-four inches in length, being measured along its pitch-line. 60 This sprocket-chain is given by the clock 13 a definite speed, preferably one inch per hour. 65

Mounted upon the sprocket-chain 17 at intervals are time-pins 19 of the form shown in Fig. 8, each being provided with a head 18. Each time-pin is encircled by a spiral spring 20, whereby it is tensioned, as indicated in Fig. 8. The normal position of each time-pin is that indicated by full lines in Fig. 8; but each pin is adapted to be pushed longitudinally into the position indicated by dotted lines in said figure, the tension of the spring 20 being such as to force the pin back into its normal position when displaced therefrom. The chain is provided with sockets 22 23, into the former of which the spring 20 may be forced, the latter being adapted to accommodate a bead 24 on the pin, according to the direction in which the pin 19 is moved. A guide 25 is provided with an angle-leaf 26 integral therewith for guiding the time-pins 19. As the sprocket-chain 17 moves upward the head 18 of each pin 19 successively engages the angle-leaf 26, and is thus forced to the right, according to the view shown in Fig. 9. 70

When any one of the pins 19 arrive at the top of the guide 25, the head 18 is no longer restrained, and the spring 20 moves into the position indicated by full lines in Fig. 8. During the time a particular head 18 is passing the guide 25, however, the tip 29 of the pin projects directly across the slot 11 to a point immediately adjacent to the front of the casing, as will be understood from Fig. 2. In order to do this, the pin 19 when displaced, 80 as indicated by dotted lines in Fig. 8, projects through a slot 27 in the plate 12. Another slot 30 is provided in the front of the casing 9 for enabling the operator to watch the card as the same drops into the slot and 85 also to enable the card to be readily recovered from the slot 11. The card 40, graduated, as shown, represents a definite interval of time, preferably six hours.

The chain is preferably twenty-four inches 90

long and makes one complete revolution in twenty-four hours, thus moving at the rate of one inch per hour. The movement of the chain is independent to a certain extent of the length of the slot 30, which is usually made about ten inches. It will be understood, however, that the chain may be made of any length desired by merely placing the sprockets apart a sufficient distance.

10 The cut or mutilation 41 is made at the beginning of a particular task or piece of work, and the cut or mutilation 42 is made at the close thereof. The interval left uncut between these two mutilations represents the time consumed. For instance, in Fig. 5 the cut 41 indicates that the owner of the card began work upon a particular piece of work at the time indicated, and the mutilation shown in Fig. 6 indicates that the work was 15 finished at the time indicated by the cut or mutilation 42. The difference—to wit, two and one-half hours—represents the time consumed by the employee during the interval after the card was first cut and before it was 20 last cut.

The upper shear 43 is provided with a cutting edge 44 and is rigidly mounted upon a head 45, which is journaled at 46 and is free to move inward under pressure of the knob 47. This shear is also provided at its extreme lower end with a lug 48. The lower shear is shown at 49 and is provided with a cutting edge 50. This shear is mounted upon a head 51, which is journaled at 52 and is 30 adapted to move inward when the knob 53 is pressed, as indicated by dotted lines in Fig. 7. This shear 49 terminates at its upper end in a head 54. In order to allow the shears to be 35 operated from the outside by means of the projecting knobs 47 and 53, the slots 55 and 56 are provided. The lower and upper shears are tensioned, respectively, by spiral springs 57 58 and normally occupy the respective positions indicated by full lines in Fig. 7. 40 Connected with the plate 12 and sunken therein is a cutting die or blade 59, against which the cutting edge 50 of the shear 49 is adapted to move, as will be understood from Fig. 2. A lug 60 supports a spring-pivot 63 and is provided with a cutting blade or die 61, mating the knife 62. This knife is provided with a slot 64, through which passes the stationary pin 65, forming a limiting-stop for the knife 62. The pivot-pin 63 is encircled by a spring 67, connected with a head 68 and with a bead 66 upon the lug 60, the arrangement being such that the pin 63 is tensioned by the spring 67. This normally maintains the knife 62 in the position indicated by full lines in Fig. 3. When the knife 62 is pressed inward or toward the back of the machine and is subsequently released, the tension of the spring 67 restores the knife to its original position, the play of which is of 65 course governed by the limiting-stop 65.

The motor mechanism for the clock 13 is shown at 13^a and is preferably mounted within a subcasing 13^b.

The operation of my device is as follows: At the beginning of a piece of work or of an allotted task an employee takes a card 40 and inserts it downward through the slot 11, the card dropping into the position indicated by dotted lines in Fig. 4. The length of the guide 25 is such that only one of the time-pins 19 is displaced at a time. Each time one of the pins thus displaced is released at the top of the guide 25 another pin is being placed under tension at the bottom of the guide. When, therefore, the card is inserted, 80 as above mentioned, it passes downwardly until it encounters the time-pin engaged by the guide 25 and is thereby temporarily supported by this pin. As the pin is moving upwardly it is clear that the position occupied 85 by the card while resting upon the pin must have a definite time relation to any fixed point within the casing—that is to say, the card will drop to a lower point at one time than at another, and while the same time-pin 90 is passing the guide as the card is inserted the higher will be the position occupied by the card while resting upon the pin. The employee now grasps the handle 47 and presses the same inward. This causes the cutting 95 edge 44 of the shear 43 to split the card longitudinally at a point comparatively near one of its edges. The bead 48 also engages the blade or knife 62, forcing the same inward. This blade or knife and the cutting 100 edge 44 coacting together complete the mutilation of the card, as indicated in Fig. 5. The employee now inserts his fingers into the slot 30, and thus removes the card which he retains in his possession for the time being. I do 105 not limit myself, however, to any particular means for removing the card. When the work is finished, he again inserts the same card and presses the knob 53 inward, thus actuating the lower shear 59. The bead 54 110 now moves the blade or knife 62, and the latter, together with the cutting edge 50 of the shear 49, mutilates the card, as indicated at 42 in the lower portion of Fig. 6. The time required in doing the particular piece of 115 work is of course represented by the uncut portion of the card 40, which necessarily represents the distance upward through which the card travels while the work of the employee was being executed. Meanwhile any 120 other number of employees may insert their respective cards and cut the same without interfering in any manner with each other.

If desired, the cards 40 after being cut, as indicated in Fig. 6, may be passed through a 125 measuring instrument for the purpose of automatically reducing the time represented by the uncut portion of the card to its equivalent in dollars and cents. To this end I have invented an instrument which I call a "com- 130

puter," and which will subsequently form the subject-matter of a separate application.

From the above description it will be noted that my device contains separate mechanisms for cutting oppositely-disposed portions of the same card and that the portion cut off is completely removed without the aid of an auxiliary appliance.

Having thus described my invention, I claim as new and desire to secure by Letters Patent—

1. In an apparatus of the character described, the combination of a member provided with a slot for holding a card, a blade 15 for cutting said card, a shear provided with a portion for engaging said blade and also with a cutting portion for engaging said card directly, means for actuating said shear, and time-controlled mechanism provided with 20 movable members for controlling the positions which may be assumed by said card.

2. In an apparatus of the character described, the combination of a casing provided with a slot for holding a card, a time-controlled member provided with a portion protruding into said slot for the purpose of positioning said card relatively to said casing, shearing mechanism for cutting said card at a point adjacent to one of its ends, and separate shearing mechanism for cutting said card at a different time from the other of its ends, so that the uncut portion of said card represents the lapse of time between said cuttings.

3. The combination of time-controlled mechanism for stopping a card at a point relative to a fixed point, and mechanism for removing from said card different quantitative portions thereof so as to leave other quantitative portions of different sizes representing different periods of time.

4. The combination of time-controlled mechanism provided with a movable member for stopping a card in different positions at different moments of time, and mechanism for removing from said card different portions thereof according to the different relative positions occupied by said cards, the lengths of certain portions remaining representing different periods of time.

5. The combination of time-controlled mechanism provided with a movable member, means for sustaining a loose card to be lodged against said movable member, the relative position of said card when lodged against said member being thus controlled by the time of said lodgment, and means for cutting off different quantitative portions of said card.

6. The combination of time-controlled mechanism provided with a movable member, a stationary member provided with a

slot disposed adjacent to said time-controlled mechanism and adapted to hold a loose card when dropped into said slot so as 65 to lodge against said movable member, the relative position assumed by said card when thus lodged being controlled by the relative position in which the movable member chances to be found at the moment when 70 said card is dropped, and means for cutting said card, the nature of the cut varying according to the relative position occupied by said card.

7. The combination of time-controlled 75 mechanism provided with a movable member adapted to support a loose card lodged thereagainst, the position of said card varying with the position of said movable member, and means for cutting different quantitative portions of said card, said different portions representing the respective moments of beginning and completing a particular piece of work.

8. The combination of time-controlled 85 mechanism provided with a movable member, means for holding a loose card to be lodged against said movable member, and separate mechanisms for cutting different portions of said card at different moments of 90 time.

9. The combination of sprocket-wheels, a sprocket-chain mounted thereupon and provided with a time-pin, clock mechanism for actuating one of said sprocket-wheels, thus 95 causing the continuous movement of said sprocket-chain and said time-pin, a member provided with a slot disposed adjacent to said time-pin, guide mechanism for causing said time-pin to protrude into said slot so as 100 to temporarily support a card therein, and means for indicating upon said card the approximate time upon which said time-pin supports said card.

10. The combination of time-controlled 105 mechanism provided with a movable member, mechanism provided with a slot disposed adjacent to said movable member, means for holding a loose card to be dropped into said slot and lodged against said movable member, and separate cutting mechanisms spaced apart and adapted to operate upon different portions of said card for the purpose of indicating upon said card different moments of time when said card engages 115 said movable member.

In testimony whereof I have signed my name to this specification in the presence of two subscribing witnesses.

JOHN GUY WYNN.
